UNITED STATES PATENT OFFICE

1,952,559

CIGARETTE MACHINE

Samuel C. Miller, Louisville, Ky., assignor to
 Jones-Miller-Veeneman Corporation, Louisville, Ky., a corporation of Kentucky

Application November 8, 1932, Serial No. 641,782

3 Claims. (Cl. 131—43)

The present invention relates to improvements in cigarettes and method and means for making same, and has for an object to provide an improved protected cigarette in which the same is wrapped in "Cellophane" or some other equivalent moisture-proof external wrapper, whereby the condition of the tobacco may be preserved for long periods of time and prevented from drying out and deteriorating.

- 10 Another object of the invention is to provide an improved method whereby cigarettes may, in their manufacture, be wrapped in "Cellophane" or the like in addition to the usual rice paper wrapper.
- 15 A further object of the invention is to provide an improved machine whereby the articles above described may be made, and it is a feature of the invention that the present practice and apparatus is not departed from materially, but the adjuncts, by which the improved article according to the invention is made possible, are in the nature of accessories which are easily and inexpensively added to the present type of equipment.

With the foregoing and other objects in view, 25 the invention will be more fully described hereinafter, and will be more particularly pointed out in the claims appended hereto.

In the drawing, wherein like symbols refer to like or corresponding parts throughout the 30 several views,

Figure 1 is a top plan view of an apparatus constructed in accordance with the present invention.

Figure 2 is a side elevation of the same with parts broken away and parts shown in section.

35 Figure 3 is a perspective view of the article produced, and

Figure 4 is a section taken on the line 4—4 in Figure 3.

Referring more particularly to the drawing one 40 embodiment of a machine is shown in which the usual rice paper or cigarette paper is represented as originally occupying a roll 5, the paper being drawn off from this roll and fed into a shaping thimble 6. The shaping thimble tapers longitudinally and is formed with convergent upper walls 7 for the purpose of rolling the paper 5 into tubular form.

Tobacco occupying a hopper 8 is fed through a spout 9 to the paper 5, within the former or 50 thimble 6. The adhesive roll is indicated at 10, such roll being preferably driven at the same speed as the movement of the paper 5. The roll 10 receives adhesive and supplies it to the paper 5, the paper being overlapped and the pressure rolls or other means 11 being employed to

compress the overlapped edges of the paper together whereby to affix same.

The tube 12 through which the filled paper is drawn after passing the rolls 11 will apply pressure also to fasten the seam in the paper joint. A roll of "Cellophane" or like paper is indicated at 13 and the same is brought down through a slot 14 near the end of the tube 12 and at the upper portion of said tube. The "Cellophane" paper passes beneath an up-turned lip 15 on a former or thimble 16 similar to the thimble 6, except that the same is turned on its axis through 180°, so that the tapering or flaring walls 17 are disposed beneath and not uppermost as in the case of the walls 7. The thimble 16 will also be of tapering form in order to shape the "Cellophane" in a tube or cylinder about the filled paper coming from the tube 12.

The "Cellophane" is sealed by an adhesive applying roller or other device 18 and by the use of pressure rolls 19 and a pressure tube or trough 20.

In this way "Cellophane" is caused to encase the cigarette during the process of manufacture. The cigarettes are cut off in lengths as required by the knife 21. The parts may all be actuated by means of a line shaft 22 having appropriate gearing as indicated.

The above apparatus is similar in form and operates similarly to that shown in the prior patent to Simon No. 1,117,527, granted November 17, 1914.

In Figures 3 and 4, I have shown the improved cigarette consisting of the inner filler 23 of tobacco, the outer customary rice paper wrapper 24 sealed, as indicated at 25, and the external "Cellophane" wrapper 26 sealed or joined, as indicated at 27.

In Figure 3 this cigarette article is also shown as having "Cellophane" or the like capsules 28 encasing the ends thereof, whereby to further protect the tobacco against contamination and drying. These capsules 28 are similar to the capsules used for containing medicines.

Of course, the invention is applicable to various other types of cigarette making machines and only one embodiment of the invention is shown herein.

In use, the capsules 28 are removed and discarded and the "Cellophane" tube will be sufficiently large to permit pushing the cigarette out of the tube or allowing it to slip out by gravity when the article is turned endwise.

It is obvious that various changes and modifications may be made in the details of construc-

tion and design of the above specifically described embodiment of this invention without departing from the spirit thereof, such changes and modifications being restricted only by the scope of the following claims.

5. What is claimed is:—

1. In an apparatus for forming moisture-proof cigarettes, a former for forming cigarette paper into tubular form about a filler of tobacco, and a second former for receiving "Cellophane" or the like and shaping the same in tubular form about the first mentioned paper, said second former forming an extension of the first mentioned former.
- 15 2. In an apparatus for the manufacture of moisture-proof cigarettes, a former for shaping cigarette paper into tubular form about a filler of tobacco, means for sealing the edges of the cigarette paper, a second former for receiving "Cellophane" or the like paper and fashioning the same in tubular form about the cigarette paper, and means for sealing the edges of the "Cello-
- 20

phane" paper about the cigarette paper, said former and said sealing means for the "Cellophane" paper forming an extension of the former and sealing means for the cigarette paper.

3. In an apparatus for the manufacture of moisture-proof cigarettes, a former for shaping cigarette paper into tubular form about a filler of tobacco, means for sealing the edges of the cigarette paper, a second former for receiving "Cellophane" or the like paper and fashioning the same in tubular form about the cigarette paper, and means for sealing the edges of the "Cellophane" paper about the cigarette paper, said former and said sealing means for the "Cellophane" paper forming an extension of the former and sealing means for the cigarette paper, the seam formed by the former and sealing means for the "Cellophane" paper being in a line not coincident with the seam formed by the former and sealing means for the cigarette paper.

SAMUEL C. MILLER.
